UNITED STATES PATENT OFFICE.

WYLIE G. WILSON, OF JERSEY CITY, NEW JERSEY.

BOILER BLOW-OFF APPARATUS.

Application filed April 16, 1925. Serial No. 23,502.

To all whom it may concern:

Be it known that I, WYLIE G. WILSON, a subject of the King of Great Britain, and resident of Jersey City, in the county of 5 Hudson and State of New Jersey, have invented certain new and useful Improvements in Boiler Blow-Off Apparatus, of which the following is a specification.

This invention relates to an improvement 10 in an apparatus adapted for controlling the blowing-off of water from steam boilers. A particular object of the invention is to provide means by which a valve interposed in the blow-off pipe to control the flow of water 15 from the boiler in the operation of blowing-off the boiler may be opened in substantial balance, thus avoiding dangers incident to the opening of such a valve under conditions where water is flowing under a powerful 20 head or pressure.

In United States Letters Patent issued to this applicant entitled "Valve control", dated February 19, 1918, No. 1,256,759, this applicant disclosed the importance of providing means whereby the valve interposed in the blow-off pipe should be opened in approximate balance. It is deemed unnecessary to do more than to refer to that patent 25 for the purpose of stating the problem and 30 its solution, so far as the apparatus therein disclosed was capable of overcoming the difficulties involved.

It will be noted from an examination of 35 said patent that there are two valves interposed in the blow-off pipe in tandem, one being nearer the boiler and the other farther therefrom. The apparatus provides means by which the valve farther from the boiler is maintained closed during the operation 40 of opening the valve nearer the boiler, the theory being that, under normal conditions, the space between the valves would be constantly maintained full of water; and consequently the valve nearer the boiler would 45 in like manner be maintained continuously in balance. This system operates with entire satisfaction when the valves are being constantly operated, but it transpires that the valve farther from the boiler, being subject to the rapid flow of water, possibly 50 carrying gritty substances in suspension, is affected by such flow in a manner to produce what is known as "wire-drawing", or other forms of abrasion; and consequently in the 55 course of time said valve farther from the boiler is found in a condition where it can-

not permanently retain the water confined between the two valves, so that when both valves are closed for a considerable time the water lying between the valves may wholly 60 or partly leak out through the valve farther from the boiler, and leave the space between the said valves either wholly or partly empty. Hence if the valve nearer the boiler were opened under such conditions there 65 would be no water between the valves to operate as a balance for the fluid pressure bearing upon the valve nearer the boiler, with the result that the opening of the valve nearer the boiler would operate detrimentally 70 upon said valve, as fully stated in said patent.

The object of this invention is to provide means by which, even under these exceptional conditions, the valve nearer the boiler 75 will be placed in substantial balance before it is opened. This is accomplished in the instant case by leading steam under pressure from the boiler to fill the space in the blow-off pipe between the valves, and opening the valve nearer the boiler under conditions where said valve is substantially 80 balanced between the steam pressure on one side and the water pressure on the other 85 side thereof.

The invention is illustrated in the accompanying drawing, which is an elevation.

The parts are designated by numerals, like numerals referring to like parts.

1 is a steam boiler, and 2 a blow-off pipe. 90 3 is a valve interposed in said blow-off pipe, this valve being designated as the one nearer the boiler; while 4 is another valve interposed in said blow-off pipe, designated as the valve farther from the boiler. 5 represents, without further description, the apparatus fully described in said patent No. 1,256,759. 6 is a section of pipe interposed 95 in the blow-off pipe 2 between said valves. 7 is a pipe communicating between the boiler 100 and said section 6 of the blow-off pipe 2, and 8 is a valve interposed in said pipe 7.

When it is desired to blow-off the boiler, the valve 8 is first opened, thus filling the chamber between said valves 3 and 4 with 105 steam under pressure. (Even though the valve farther from the boiler may be in a leaky condition, the supply of steam is intended to be sufficient to compensate for such leakage and maintain the valve nearer the 110 boiler in balance, as stated.) The valve 3 is then opened in substantial balance be-

tween the water and steam pressure. Then the valve 8 is closed, and the valve 4 is opened to blow-off the boiler; and vice versa, when it is desired to cut off the flow from the 5 boiler, the valve 4 is first closed, and then the valve 3, as stated in said patent.

While in this application the tandem valve structure and means of operation disclosed in said patent are illustrated, it is 10 not necessary for the purpose of this invention that that particular apparatus should be employed. The valves 3 and 4 may be independently and manually operated in association with the steam pressure, as stated. There are, however, advantages in employing the tandem valve cooperative mechanism illustrated and described in said patent, and it is for this 15 reason that the structure shown in said patent is illustrated as a preferred form of construction.

Claims:

1. In a boiler blow-off system, a blow-off pipe leading from the boiler with two valves 25 interposed in said pipe, one being nearer the boiler and the other farther removed therefrom, and means to operate said valves, means to introduce steam pressure from the boiler to the blow-off pipe between said 30 valves, and means to control said flow of steam pressure, so that when said valves are closed and steam pressure is introduced into said pipe between said valves, the valve nearer the boiler may be opened in balance 35 between the water in the boiler and such steam pressure.

2. In a boiler blow-off system, the combination with a boiler having a blow-off pipe leading therefrom, of two valves included in the blow-off pipe in tandem, valve actuating 40 mechanism connecting the sealing members of said valves for operation in predetermined sequence, and a valved conduit leading from the steam chamber of the boiler into the space between the sealing members 45 of said valves, whereby steam pressure from the boiler may be admitted into said space for the purpose of producing a substantially balanced condition of pressures on both sides of the valve nearer the boiler. 50

3. In a boiler blow-off system, a blow-off pipe leading from the boiler, with two valves interposed in said pipe, one being adjacent the boiler and the other farther removed therefrom, and means for controlling the operation of said valves so that the valve farther from the boiler cannot be opened until the valve nearer the boiler is first opened, and the valve nearer the boiler cannot be closed until the valve farther from the boiler is 60 first closed, and means to introduce steam pressure from the boiler to the boiler blow-off pipe between said valves, and means to control said steam pressure, so that when said valves are closed and steam is introduced 65 into said blow-off pipe between said valves, the valve nearer the boiler may be opened in balance between the water in the boiler and such steam pressure.

Signed by me at Jersey City, N. J., this 70
15th day of April, 1925.

WYLIE G. WILSON.
